STOVE CONSTRUCTION

George E. Pickup, Newark, Ohio, assignor to The Wehrle Company, Newark, Ohio, a corporation of Ohio

Application July 14, 1932, Serial No. 622,468

12 Claims. (Cl. 126—39)

The invention pertains to cook stoves or ranges and has more particular reference to an improved mode of construction for stoves of the so-called table top type.

5 The object of the invention is to produce a practical stove construction of the character indicated at a lower cost than has heretofore been possible without sacrificing neatness of appearance, rigidity, and durability.

10 In the accompanying drawings,

Figure 1 is a fragmentary front elevational view of a stove embodying my invention.

Fig. 2 is an end view with parts broken away to show details of construction.

15 Fig. 3 is an exploded perspective view showing various parts employed in constructing the stove body.

Fig. 4 is a fragmentary perspective view illustrating the matter of mounting and guiding 20 the utility drawer.

Fig. 5 is a fragmentary transverse sectional view through the front frame and the forward edge portion of the central partition wall between the oven section and the cooking top 25 section.

The improved stove is built up from a number of sections or units separately constructed and enameled and subsequently assembled into a rigid structure. While the number and character of the units may vary, they include in the present instance two major units of which one is a base unit providing a base frame 7, an intermediate vertical partition plate 8, and a rear wall plate formed from one sheet of metal and 30 providing rear walls 9 and 10 for the oven and cooking top sections respectively; and the other an inner oven unit generally U-shaped in form and having parallel inner side wall plates 11 and 12, an inner top wall plate 13, and an inner rear wall plate 14. In the embodiment herein shown, the oven section is of the insulated type and the inner oven unit is mounted at one 35 end of the base frame in cooperative relation to the partition plate 8 and the rear wall 9 of the base unit to form two of the outer side plates 40 of the oven section.

To the two major units assembled as above indicated, I apply a plurality of auxiliary units. Thus two separately formed outer side or end 45 plates 15 and 16 are mounted at opposite ends of the base frame; a top plate 17 overlies both the major units; and a front frame 18 substantially completes the body. The partition plate 8 of the base unit forms the inner end wall of 50 the cooking top section of the stove, and the end

plate 16 forms the outer end wall of said section, the rear wall 10 thereof being formed by the rear plate of the base unit. One end of the top plate 17 forms a top finishing plate 17a and the other end is cut away to form a cooking 60 top frame 19. The front frame unit 18 provides door frames for the usual closures including, in the present instance, an oven door 21 (Fig. 1), a broiler door front 22, two utility door fronts 23 and 23a, and a manifold cover 65 plate 24.

The base frame 7 as herein shown (Figs. 1 and 3) is made from a single elongated sheet of relatively heavy gage metal rectangular in form and having opposite end portions of substantial size cut out so as to form front and rear frame members 25 and 26, end members 27 and 28, and a relatively wide central frame member 29. The portions of the plate thus removed in forming the base frame may, of course, be utilized in making other parts of the 70 stove. For the sake of rigidity, the opposite side edges of each of the frame members is flanged downwardly so as to make the frame members of substantially inverted channel form. 75

The intermediate partition plate 8 of the base unit is suitably secured in position approximately centrally of the intermediate frame member 29 of the base, being for this purpose provided with a flange 30 which is spot welded 85 to the base frame. The rear walls 9 and 10 are as above indicated formed from one sheet of metal which is secured to the rear depending flange of the base frame and to a flange at the rear edge of the partition plate 8. Preferably these parts are secured together by spot welding. 90

The plates 11, 12 and 14 of the inner oven unit are preferably made from a single sheet of metal, and are preferably secured to the top 95 plate 13 by spot welding, said plate 13 having for this purpose upturned flanges at each of its edges, as shown clearly in Fig. 3. At the lower edges of the plates 11, 12 and 14 inturned flanges 31, 32 and 33 are provided, these flanges being apertured for the purpose of bolting the inner oven section in position on the base frame, which latter for this purpose is provided with suitable openings 34. Similarly, the side plates 11 and 12 are provided at their front edges with 100 apertured outturned flanges 35 and 36 adapted to be secured to the main front frame in a manner which will later be described.

The outer side plate 15 of the oven section is 110 mounted in interengaging relation to the frame

member 27 of the base frame and for this purpose carries at its lower edge and upon the inner side thereof a plurality of bracket members forming hooks 39 spot welded to an outwardly offset lower marginal portion 40 of the plate 15. The hooks 39 have down-turned tongues 41 adapted to enter slots 42 formed in the frame member 27. At its front and rear edges the plate 15 has flanges 43 and 43^a respectively secured as by means of fastening screws to the rear oven wall 9 and to the front frame 18.

An intermediate top plate 44 is provided for the top wall of the oven section so as to form a flue space with the inner top plate 13. Said plate 44 has down-turned side flanges 45 adapted to fit over the upper edges of the plates 11 and 12 (Fig. 1) and secured thereto as by means of screws entered through holes 46. The plate 44 is spaced from the inner top plate 13 and the flue space thus formed communicates at its rear edge through an opening 47 with a space between the inner rear plate 14 and the outer rear wall plate 9 of the oven section, the latter being provided with a flue hole 48 (Fig. 3). The forward edge of the inner top plate 13 of the oven terminates short of the corresponding edge of the plate 44 to form a passage 49 (Fig. 2) to permit the passage of products of combustion upwardly into the flue space between the plates 13 and 44, and preferably baffle plates 50 are secured on the plate 13 to retard the passage of the hot gases to the opening 47 at the rear.

The top plate 17 is formed from a flat sheet of metal and has down-turned flanges at each of its four edges. The end plate 17^a overlies the oven section and the side flanges are so proportioned as to fit downwardly over the upper edges of the front frame and the plates 9 and 15. Thus a front flange 51 is arranged to fit over the upper edge portion of the front frame 18 (Figs. 2 and 3); a rear flange 52 fits downwardly over the upper edge of the rear plate 9 and is secured thereto by means of screws; and an end flange 53 with inturned edges engages the upper edge portion of the end plate 15.

At the front and rear edges of the intermediate plate 44 are upstanding flanges 54 and 55 serving to space the oven top plate 18 from the plate 44, this space being preferably filled with suitable insulating material 56 (Fig. 2). The spaces formed within the hollow side walls of the oven are, of course, similarly filled with insulation material.

The outer end plate 16 of the cooking top section is mounted on the base frame in a manner similar to the plate 15 of the oven section, being for this purpose provided with hooks 57 engaging in slots in the frame member 28 of the base member. Also the plate 16 has a rear securing flange 58 fastened to the rear wall plate 10 of the base unit, and a front flange 59 to be fastened by screws to the front frame.

The cooking top frame 19, provided by the end of the top plate opposite the oven top 18, engages the upper edges of the vertical wall plates 8, 10 and 16 forming the walls of the open top section. For this purpose the rear flange 52 of the top plate fits downwardly over the upper edge of the rear plate 10 and secured thereto; and the end flange 53^a engages the upper outer edge of the end plate 16. Seated within the frame 19 is a burner top plate 62 formed of sheet

metal and having openings for the top burner of which only one is shown at 63.

The main front frame unit 18 is formed from two castings 64 and 65 each substantially rectangular in form and secured together so as to provide an oven door frame 66, a broiler drawer frame 67, and a front frame 68 for the cooking top section. The two castings 64 and 65 are preferably secured together by means of screws 69 (Fig. 5), the two parts having an interfitting relation for this purpose with the casting 64 formed with an extension 70 overlapped by a channel shaped section 70^a of the casting 65.

The frame 18 thus constructed is applied to the front of the oven unit and the open top section after the latter have been assembled and suitably secured in position. In the present instance, the lower frame members are provided with a plurality of inwardly projecting bosses 71 of which one is shown in Fig. 2 to receive screws entered through the down-turned flange at the front of the base frame from the inner side thereof, said flange being provided with suitable openings 72 for this purpose. In fastening the end plate flange 59 to the front frame, bosses similar to the bosses 71 may be provided on the end member of the frame to receive screws entered through apertures 72^a in the flange 59 of the end plate 16.

At the upper front edges of the two major sections the frame 18 is secured in position by means of bolts 73 (Fig. 2) entered through angle brackets 74 spot welded to the underside of the top finishing plate 17 and depending therefrom in rearwardly spaced relation to the front flange 51 of the top plate. To receive the bolts 73, the front frame is provided with apertures 75 formed in the closure seating flanges 76 of the frame.

As shown in Fig. 5, the front frame member is provided with lugs 77 and 77^a forming with parts of the front castings grooves for receiving the front edge portions of the oven wall plates 8 and 11. At its upper edge the plate 8 is flanged as at 8^a for engagement with the underside of the top plate 17.

Within the oven section is a horizontal partition 78 dividing the same into an upper or baking oven and a lower or broiler oven. Beneath the partition 78 is an oven burner 81 supported in any suitable manner. 82 designates generally a broiler drawer suitably mounted for front to rear sliding movement on tracks 83, which latter may be spot welded to the frame members 27 and 29 of the base. 84 designates roller brackets for additionally supporting and guiding the drawer whose front 22 is arranged to seat in the frame 67 of the front frame unit. Inasmuch as the broiler drawer structure forms no part of the invention, it need not be described in detail.

The main oven door 21 is suitably hinged at its lower edge, the hinges being generally designated 85 in Fig. 2.

The cooking top section provides in its upper portion a burner box in which is supported, preferably by means of the front frame, a manifold 86 for supplying the top burners. A front cover plate 24 pivotally mounted on hinge brackets 88 serves to close the burner box.

The lower portion of the cooking top section provides a compartment having in the present instance two utility drawers 89 carrying the closure fronts 23 and 23^a. The lower drawer may be slidably mounted on tracks 90 of double angle formation spot welded to the frame members 28 and 29 of the base. The sides of the

drawer carry guide brackets 91 engaging the tracks (see Fig. 4) to hold the drawer in position thereon. 92 (Fig. 4) are stop fingers formed on the tracks to limit the outward movement 5 of the drawer. The upper drawer may be mounted for front to rear sliding movement in any preferred manner.

To support the body of the stove, legs 93 are fastened at the corners of the base frame which 10 for this purpose is provided with corner brackets 94 substantially triangular in form and having upstanding corner flanges 95 adapted to fit snugly within the corners of the base frame formed by the outer depending flanges. The 15 flanges are spot welded to the down-turned flanges of the base frame. The legs have top plates 96 which are secured to the corner brackets as by means of bolts 97 which are entered from beneath and engage in tapped holes in the 20 corner brackets.

The rear edge of the stove body may have secured thereto a back plate 98. 100 designates generally a towel bar of U-shaped form having its legs slidably mounted within the flue space 25 between the inner oven plate 13 and the intermediate top plate 44, and its bight projecting outwardly to the outer side of the oven section.

By reason of the construction above set forth, it is possible to reduce substantially the cost 30 of manufacture due principally to the fact that the stove is composed of separate units each having its several component parts secured together and completely enameled before being assembled with other units. Thus the base unit 35 consisting in the present instance of the base frame 7, vertical partition plate 8, and rear wall plates 9 and 10, together with the broiler and utility drawer guide tracks, is constructed, assembled and enameled as a unit. Similarly, the 40 inner oven unit is completely constructed and enameled and thereupon secured in cooperative relation to the base unit, whereupon the end plate units 15 and 16 and the front frame unit 18, each having been previously enameled, are applied to the base and oven units. Finally the 45 body is completed by the application of the top plate 17, it being observed that the plate 17 engages with the end plates 15 and 16 to hold them in position.

50 It will also be observed that the front frame unit is secured in position in such a way that when the several closure members are in closed position no bolts or screws are exposed, and the end plates 15 and 16 are similarly mounted so as to leave no exposed fastening devices.

55 Thus I have provided a method of stove construction which not only permits of a reduced cost of manufacture and a rigid construction, but which also renders it possible to obtain a neat and attractive appearance.

60 I claim as my invention:

1. A cook stove having a body comprising a base unit including a base frame, a rear wall plate, and a central transverse plate rigidly secured to the base frame in perpendicular relation, an end plate unit adapted to be mounted at one end of the base frame, an inner oven unit having side, rear and top wall plates secured together and adapted to be mounted as 65 a unit on the base frame in cooperative relation to the plates of the base unit and said end plate unit to form an oven compartment at one end of the base frame with hollow side and rear walls, means including a top frame 70 plate having one end portion forming a hollow

top wall for the oven compartment and another end portion forming a cooking top frame, a second end plate unit mounted on the end of the base frame opposite the oven unit and cooperating with said rear plate of the base unit 80 and with said cooking top frame to form a cooking top section, and a front frame applied to the forward edges of the base frame and the cooking top frame.

2. A cook stove having a body comprising a 85 base unit including a base frame, a rear wall plate coextensive with the base frame, and a central transverse plate rigidly secured to the base frame and to said rear wall plate, two end plate units mounted upon the ends of the base frame in perpendicular relation to the rear wall plate, an inner oven unit having inner side and rear plates and mounted on said base frame in cooperative relation to said rear wall plate, said transverse plate, and one of said 90 end wall units to form an oven compartment having hollow side and rear walls, a top plate for the oven unit, and a top frame having one end portion coacting with said top plate to form a hollow top wall and another end portion coacting with said rear wall plate, said central plate and the other one of said outer side plates to form a cooking top section.

3. A cook stove having a body comprising a 95 base unit including a base frame, a rear wall plate coextensive with the base frame, and a central transverse plate rigidly secured to the base frame and to said rear wall plate, two end plate units mounted upon the ends of the base frame in perpendicular relation to the rear wall plate, an inner oven unit having inner side and rear plates and mounted on said base frame in cooperative relation to said rear wall plate, said transverse plate, and one of said end 100 wall units to form an oven compartment having hollow side and rear walls, an inner top plate for the oven unit, and a main top plate having one end portion coacting with said inner top plate to form a hollow top wall and another end portion coacting with said rear wall plate, 105 said central plate and the other one of said outer side plates to form a cooking top section, said top frame having a dependent front edge portion, and a front frame secured to the base and having its upper edge portion enclosed by 110 said down-turned edge portion of the top frame.

4. A cook stove having a body comprising a 115 base unit including a base frame and a rear wall plate rigidly secured thereto, an oven unit having a plurality of vertical wall plates secured together and mounted on one end of said base frame, an end plate unit mounted on the base frame at the end opposite the oven unit and disposed perpendicular to said rear wall plate, a front frame secured to the front edges of the base 120 frame and said end plate unit, and a main top plate formed of sheet metal and providing a finishing top for the oven unit and a cooking top frame, said top plate having its forward edge portion secured to said front frame.

5. A cook stove having a body comprising a 125 base frame formed from a flat sheet of metal and having downturned edge flanges, means mounted on said frame to form an oven section at one end and a cooking top section at the other 130 end, said means including a rear wall plate, end wall plates, and an intermediate partition plate all substantially coextensive in height, said end wall plates having their lower edges in overlapping relation to the end flanges of the base 135

frame, a front frame secured at its lower edge to the front edge flange of the base frame, and a top plate having down-turned edge portions engaging the upper ends of said end plates and the upper edge of said front frame in overlapping relation.

6. A cook stove having a body comprising a base frame, means mounted on said frame to form an oven section at one end and a cooking top section at the other end, said means including a rear wall plate, end wall plates, and an intermediate partition plate all substantially coextensive in height, a front frame secured at its lower edge to the front edge of the base frame, and a top plate having down-turned edge portions engaging the upper ends of said end plates and the upper edge of said front frame in overlapping relation, certain of the vertical wall plates being permanently secured to the base frame and to each other to form a rigid base unit and the other vertical wall plates being detachably mounted on the base frame.

7. A cook stove having a body comprising a base frame, means mounted on said frame to form an oven section at one end and a cooking top section at the other end, said means including a rear wall plate, end wall plates, and an intermediate partition plate all substantially coextensive in height, a front frame secured at its lower edge to the front edge of the base frame, and a main top plate having down-turned edge portions engaging the upper ends of said end plates and the upper edge of said front frame in overlapping relation, said partition plate being permanently secured at its lower edge to the base frame and having a flanged upper edge engaging the underside of said top plate.

8. A stove body having a base frame, a rear wall plate coextensive with and spot welded to the rear edge of the base frame, a central partition plate spot welded to the base frame and to said rear plate, two end plates having hooks on their inner sides engaging with the base frame, and a top plate formed from a single sheet of metal and having downturned edges engaging the upper ends of said end plates at the outer sides thereof.

9. A cook stove having a body comprising a base frame, a rear wall plate secured at its

lower edge to the base frame, two end plates having hooks on their inner sides engaging with the base frame, a front frame secured at its lower edge to the base frame and to the front edges of said end plates, and a top plate having down-turned edge portions overlapping the upper ends of said end plates and secured at its front and rear edges to the rear wall plate and the front frame respectively.

10. A cook stove having a body comprising a base frame, a rear wall plate secured at its lower edge to the base frame, to end plates having hooks on their inner sides engaging with the base frame, a front frame secured at its lower edge to the base frame and to the front edges of said end plates, and a top plate having down-turned edge portions overlapping the upper ends of said end plates and secured at its front and rear edges to the rear wall plate and the front frame respectively, said top frame also having a down-turned front edge portion overlapping the upper edge of the front frame.

11. A cook stove having a body comprising an oven section and a cooking top section, a base plate, a top plate and a front frame common to both of said sections with the upper edge portion of the front frame covered by the front edge portion of the top frame and secured thereto, both of said sections further having end plates with their lower edges overlapping the end of the base plate and each having retaining means engaging with the top of the base plate.

12. A cook stove having a body comprising an oven section and a cooking top section, a base plate having downturned edge flanges, a top plate and a cast front frame common to both of said sections with the upper edge portion of the front frame covered by the front edge portion of the top frame and secured thereto, both of said sections further having end plates with their lower edges overlapping the ends of the base plate and each having retaining means engaging with the top of the base plate, and screws entered through the front flange of the base plate into said cast front frame rearwardly thereof.
